JEWELRY FINDING

Pearl F. Ashton, Providence, R.I., assignor to Rolyn Tool
& Finding Company, a corporation of Rhode Island

Application September 8, 1959, Serial No. 57,473

Term of patent 3½ years

(Cl. D45—19)

Fig. 1 is a top plan view of a jewelry finding showing my new design; and

Fig. 2 is a side elevational view thereof.

I claim:

The ornamental design for a jewelry finding, substantially as shown.
